(57) **CLAIM**

The ornamental design for a bottle carrier, as shown and described.

DESCRIPTION

FIG. 1 is a front view of a bottle carrier according to my new and ornamental design, shown with a bottle and a keyfob; FIG. 2 is a rear elevation view thereof; FIG. 3 is a left side elevation view thereof; FIG. 4 is a right side elevation view thereof; FIG. 5 is a top plan view thereof; FIG. 6 is bottom plan view thereof; FIG. 7 is a top rear perspective view thereof; and, FIG. 8 is a bottom front perspective view thereof. The broken line showings of a bottle and a keyfob in FIG. 1 are directed to environment and form no part of the claimed design. The tab portion of the bottle carrier shown in broken lines forms no part of the claimed design.

1 Claim, 6 Drawing Sheets
